BODY-SUPPORTED INFANT'S CHAMBER POT

Neva R. Deardorff, New York, N. Y.

Application January 26, 1946, Serial No. 643,568

2 Claims. (Cl. 4—110)

1

The invention relates generally to toilet utensils, and more particularly to a "pottie" for small infants.

The general object of the invention is to provide a novel pottie particularly useful for very young infants and arranged so that it may be readily supported on an adult's lap when in use by the infant.

More specifically, it is an object to provide a novel pottie provided with laterally extending supporting members which are adapted to fit over and be supported by the legs of an adult when seated so that the pottie may be held between the knees without undue strain on the adult and the infant may be seated on the pottie and held in such position with comfort.

Another object is to provide a novel pottie provided with laterally extending supporting members adapted to be supported by the legs of an adult, when seated, with the pottie held between the knees, the supporting members being provided with containers at the outer ends to hold toilet supplies, such as tissue, pins, talcum powder and the like.

Other objects and advantages will become apparent from the following description taken in connection with the accompanying drawings, in which:

Figure 1 is a transverse sectional view of a toilet utensil embodying the features of the invention.

Fig. 2 is a plan view of the device.

Fig. 3 is a sectional view taken on the line 3—3 of Fig. 1.

Fig. 4 is a view showing the manner in which the device is held.

In the care of infants, the performance of the excretory functions of an infant has frequently been provided for by the mother holding the usual type of pottie between her knees and placing the infant thereon, much as if the infant were sitting on her lap. Such practice is commonly used when the infant is too young to safely use a small seat placed on a toilet or where such small seat is not available.

Such practice, however, gives rise to some difficulty because of the muscular strain on the mother, if she attempts to hold the pottie in this manner for more than a few minutes. This difficulty does not have its effect on the mother alone, since an infant is highly susceptible to its mother's state of mind when being handled by her, and it is the accepted view of pediatricians that an infant should be in a relaxed state of mind, free from any tenseness, when being en-

couraged to perform its functions. Thus, while the purpose of the practice is to encourage and teach the infant to perform its functions at selected times, it frequently results in a condition adverse to such performance.

The present invention provides a pottie which permits holding the infant in the same manner. But it relieves the mother of all strain and consequently permits her to remain in a relaxed state of mind beneficial to the infant in performing these functions. To this end, I provide a receptacle 10 which may have the general form of an ordinary pottie, but preferably is oval rather than round, as is shown in Fig. 2, so that it 15 may be placed between the mother's knees without causing them to be spread far apart. The receptacle 10 is provided with a flange 11 on which the infant is seated. At the front end of the receptacle, a shield 12 may be provided, utilized 20 to direct the urinary stream into the receptacle, in the case of male infants.

To permit the receptacle 10 to be held without muscular strain, a pair of supports 13 are provided, extending laterally from the receptacle at 25 the upper part thereof and adapted to be rested on the mother's legs adjacent the knees, as shown in Fig. 4. Thus, the receptacle may be supported without the exertion of any muscular effort on the part of the mother. Preferably, the supports 30 13 are curved to fit over the legs and thus tend to remain in place so that the receptacle will be positioned between the knees.

The usefulness of the device may be increased by providing it with means for holding toilet supplies such as tissue, pins, talcum powder and the like. Thus, the outer ends of the supports 35 13 may be provided with small containers 14 for this purpose, the containers being accessible when the infant is seated on the receptacle 10. The 40 containers 14 also assist in holding the device in place on the mother's legs since they extend downwardly from the supports 13 at the outer sides of the legs and thereby aid in preventing the supports from slipping.

45 The device is preferably made in a one-piece construction of molded plastic material. With such a construction, the shield 12 is formed on and extends upwardly from the flange 11, while the supports 13 constitute extinctions from the flange 11. The containers 14 similarly constitute the terminal portions of the supports 13. The one-piece construction facilitates handling of the device, since it may be readily grasped and manipulated by one of the supports 13.

50 From the foregoing, it will be apparent that

I have provided a novel pottie construction adapted to be supported with the pottie or receptacle between the mother's knees when the infant is seated thereon. By providing supports for the pottie, which merely rest on the mother's legs, the pottie is held in position without the physical strain involved in attempting to clamp the ordinary pottie between her knees. The mother may thus carry on the operation with comfort and consequently will be inclined to give the infant sufficient time to perform its functions.

I claim:

1. A toilet utensil for an infant, comprising a generally oval vessel having an open top provided with a flange shaped for seating the infant thereon, and a pair of supporting members rigidly secured to the opposite sides of the vessel at the shorter diameter thereof and extending laterally from adjacent the top of the vessel, said members being curved to fit comfortably over the legs of an adult, when seated, adjacent and above the knees, and having portions at the outer ends thereof extending downwardly to fit over the outer sides of the adult's legs to hold the supporting members in place, whereby said vessel may be readily held between the adult's knees when in use by the infant.

15

2. A toilet utensil for an infant, comprising a vessel having a flanged top shaped for seating an infant thereon, a pair of supporting members rigidly secured to opposite sides of said vessel and shaped to fit over the legs of an adult, when seated, adjacent and above the knees whereby said vessel may be readily held between the adult's knees, and a pair of containers rigidly secured to the outer ends of the respective supporting members to hold toilet supplies, said container being adapted to extend downwardly at the outer sides of the adult's legs and thereby assist in holding the supports in place.
